SUPPORTING STAND

William B. Cohen and Lewis Fine, St. Paul, Minn., assignors to Stuart Products Company, St. Paul, Minn., a corporation of Minnesota

Application March 18, 1940, Serial No. 324,578

5 Claims. (Cl. 211—74)

Our invention relates to an improvement in supporting stands and more particularly for supporting stands used for the display of perfume or some similar material.

In the sale of competitive materials such as perfume, it has been found desirable to provide unique display methods to influence the purchaser to a particular brand. If one perfume is displayed more attractively than another, a purchaser will choose that brand in the absence of other differentiating features. Accordingly, expensive bottles and containers are oftentimes designed and attractive boxes and supports are provided for the bottles to create sales interest and to direct the purchasers' attention to a particular brand.

It is the object of the present invention to provide an attractive display for a series of bottles of perfume or similar material to attract the attention of prospective buyers and to form a supporting stand which will be attractive in the home. We provide a supporting standard in the general shape and formation of a floor lamp having a standard and a shade upon the standard of the same general form and proportion as the usual floor lamp. This standard is of small size and is used to support small bottles of the substance to be sold. When in use it provides an attractive addition to a dressing table.

It is a feature of our invention that our stand is particularly designed to accommodate bottles of a certain shape and size. This construction is advantageous as it guides purchasers to buy one particular brand of perfume mounted in bottles of the desired shape.

It is a feature of our invention that the bottles containing perfume may be of different color and may be supported in the position beneath the portion of the support simulating the shade of the lamp. As the liquid contained within the bottles is translucent or transparent, light shining through the lamp shade and through the bottles provides a colored light which is pleasing and attractive.

It is a feature of our invention that the bottles supported thereon may be mounted within the shade of the lamp and may be supported upon a platform which is slidable with respect to the standard of the support. By sliding this platform downwardly upon the standard, the bottles may be mounted beneath the shade to facilitate the removal of the bottles from the platform or the insertion of bottles upon the same.

It is a further feature of our invention that the standard simulating a floor lamp may be pro-

vided with a chain or cord depending from the bottle supporting platform and which may be engaged by the fingers to lower this platform. This chain or cord simulates the appearance of a chain or cord commonly used to turn a floor lamp off and on and assists in completing the effect of a floor lamp.

These and other objects and novel features of our invention will be more clearly and fully set forth in the following specification and claims.

In the drawing forming a part of our specification:

Figure 1 is a side elevation view of our standard disclosing the bottles and supporting platform in lowered position in dotted outline.

Figure 2 is a side elevation view of our standard partly in section disclosing the construction thereof.

Figure 3 is a top plan view of our standard.

The support A comprises an enlarged base 10 having a vertical standard 11 extending upwardly therefrom. The base 10 and the upright standard 11 are decorated to simulate the base and vertical standard of a floor lamp. The central portion 12 of the standard 11 is cylindrical in shape to provide a slidable support for a collar 13 encircling the same. The collar 13 is vertically slidable upon the center portion 12 of the standard 11 as will be later described.

The collar 13 is provided with a disc-shaped platform 14 terminating in an upwardly inclined marginal flange 15. The platform 14 is designed to support a series of bottles 16 as indicated in Figures 1 and 3 of the drawing, and the marginal flange 15 holds the bottles in place upon the platform.

A spring 17 encircles the cylindrical portion 12 of the standard 11 and is secured at one end 19 to the disc 14. The other end 20 of the spring 17 extends through a hole 21 in the standard 11. The spring 17 is of sufficient strength to support the platform 15 in the raised position illustrated in full lines in Figure 1 of the drawing and also disclosed in Figure 2 of the drawing. The platform 14 and the collar 13 may, however, be slidably moved downwardly so that the tops of the bottles 16 are positioned beneath the shade 22.

The shade 22 is designed to encircle the bottles 16 supported upon the platform 14. This shade 22 is supported by a supporting spider 23 having a central opening 24 therein of smaller diameter than the cylindrical portion 12 of the standard 11. The top of the cylindrical portion 12 of the standard 11 is provided with an axial pin 25 of reduced diameter with respect to the cylindrical

portion 12, and the hole 24 is designed to accommodate this pin 25. Thus the spider 23 fits over the pin 25 and is supported by the shoulder formed between the pin 25 and the cylindrical portion 12 of the standard 11.

A decorative top retaining portion 26 is provided with an axial socket 27 designed to engage the pin 25. The socket 27 may be of a size to frictionally engage the pin 25 or the pin and socket may be correspondingly threaded so that the top member 26 may be threadably engaged onto the pin 25. The decorative top retaining portion 26 holds the lamp shade in proper position normally encircling the bottles 16 upon the supporting platform 14.

In preferred form the shade 22 is formed of transparent or translucent material. When light shines through this shade and through the bottles 16 upon the platform 15, the color of the perfume within the bottles casts an attractive beam of colored light upon the shade. When the support is placed upon the dresser or table, the color of the bottles as well as the general formation of the support creates a unique and attractive display and enhances the appearance of the table in general.

In order to conveniently raise and lower the platform 14 so that the bottles 16 may be placed thereon or removed therefrom, we provide a chain 29 depending from the platform 14. By grasping this chain 29 with the fingers and exerting a downward pressure upon the chain, the platform 14 may be lowered the necessary amount to hold the bottles 16 conveniently accessible.

In accordance with the patent statutes, we have described the principles of construction of our support for bottles or the like; and while we have endeavored to set forth the best embodiments thereof, we desire to have it understood that this is only illustrative of a means of carrying out our invention, and that obvious changes may be made within the scope of the following claims without departing from the spirit of our invention.

We claim:

1. A support for bottles and the like comprising a base, a standard extending upwardly from said base, a platform encircling said standard,

said platform movable between raised and lowered positions, a shade encircling said standard and enclosing bottles placed upon said platform in raised position thereof, and means resiliently supporting said platform in raised position.

5. A support for bottles or the like comprising a base, a standard extending upwardly from said base, a sleeve slidable upon said standard, a supporting platform extending outwardly from said 10 sleeve designed to accommodate a series of bottles, a substantially frustro-conical shade encircling said standard, means securing said shade to said standard, and spring means for normally supporting said sleeve and platform in raised position to support said bottles within said shade.

15. 3. A support for bottles or the like comprising a base, a standard extending upwardly from said base, a sleeve encircling said standard and slidably thereupon between raised and lowered positions, resilient means urging said sleeve into raised position, a platform secured to said sleeve and slidably therewith designed to support a 20 series of bottles, a shade encircling the upper portion of said standard and designed to enclose said bottles in raised position of said sleeve, means securing said shade to said standard, and means secured to said platform and depending therefrom by means of which said platform may be drawn into lowered position.

25. 4. A support for bottles and the like comprising a base, a vertical standard extending upwardly therefrom, a shade depending from and encircling the upper portion of said standard and fixed thereto, and means on said standard for supporting bottles and the like within said shade 30 adjacent said standard whereby the articles placed thereon are concealed from view.

35. 5. A support for bottles comprising a base, a vertical standard extending upwardly therefrom, a shade depending from and encircling the upper portion of said standard and fixed thereto, and means slidable on said standard for supporting bottles under said shade adjacent said standard whereby the bottles placed thereon are concealed 40 from view.
